Patented June 24, 1919.

UNITED STATES PATENT OFFICE.

EDWARD E. CHERRY, OF TRENTON, NEW JERSEY, ASSIGNOR OF ONE-THIRD TO WAGER FISHER, OF PHILADELPHIA, PENNSYLVANIA, AND ONE-THIRD TO LOUIS E. LAURENT, OF NEW YORK, N. Y.

CAPSTAN AND SHEAVE BLOCK.

1,307,578.

Specification of Letters Patent. Patented June 24, 1919.

Application filed April 22, 1914. Serial No. 833,606.

To all whom it may concern:

Be it known that I, EDWARD E. CHERRY, a citizen of the United States, residing at 1140 Franklin St., Trenton, in the county of Trenton and State of New Jersey, have invented a certain new and useful Capstan and Sheave Block, of which the following is a specification.

The purpose of my invention is to align 10 a floating capstan with the hook by which it is supported so as to keep the axis of the capstan perpendicular to the line of strain and, where a sheave or sheaves are used upon the capstan block or connected with 15 it, to align the floating sheave or sheaves with the capstan.

A further purpose of my invention is to form a floating capstan and sheave combination with the parts supported from a 20 single point and with the capstan in tandem with the sheave or pair of sheaves used.

A further purpose of my invention is to provide lateral movement of a pulley wheel 25 as a means for making it accessible to thread rope into it and to provide for its retention in position against accidental side movement.

A further purpose of my invention is to retain a pulley wheel against accidental side 30 movement by pivoted means and to lock it in position by a member coöperating with a becket or rope guide.

A further purpose of my invention is to place a pair of sheaves in tandem and permit 35 insertion of rope to these wheels at any part of the length of the rope, as by side movement of the sheaves, preferably using the pair with a sheave and capstan similarly in tandem.

40 A further purpose of my invention is to provide a rigid retaining device for a pair of sheave blocks to remove the strain from the rope between.

A further purpose of my invention is to 45 use a guide for a floating capstan to maintain the line of strain upon the same at the most advantageous point on the capstan.

A further purpose of my invention is to undercut 50 a capstan ratchet and correspondingly shape the pawl to cause the ratchet to draw the pawl into engagement with the ratchet teeth.

While appreciating that my invention may be embodied in many other forms than

those shown by me, I have selected the several illustrations shown as not only practical, efficient and inexpensive but as presenting the principles of my invention in the best form now known to me. 55

Figure 1 is a broken front elevation of 60 a floating capstan embodying one form of my invention.

Fig. 2 is a side elevation of the structure seen in Fig. 1.

Fig. 3 is a partial section of Fig. 1, taken 65 upon line 3—3 thereof, with capstan parts removed and showing the lower part of the device only.

Fig. 4 is a broken front elevation of the structure of Fig. 1 in tandem connection 70 with a sheave block and with another sheave block supported therefrom.

Fig. 5 is a broken side elevation of the structure of Fig. 4.

Fig. 6 is a front elevation of a capstan 75 block similar to that of Fig. 1 in permanent tandem connection with a sheave and roped up with a sheave block having tandem sheaves.

Figs. 7 and 8 are sections, taken through 80 the sheaves, capstan, rope and guards only, upon lines 7—7 and 8—8 respectively, of Fig. 6, the rope and chain being removed and the remaining parts being in elevation.

Similar numerals of reference indicate 85 like parts.

In the form shown in Figs. 1 and 2, I indicate a capstan block adapted to be used without any sheaves and capable of direct use for pulls requiring comparatively little 90 strength, such for example as stretching fence sections.

In these the capstan 1 is connected with the body 2, and handle 3 by ratchet connections hereinafter more fully described 95 and illustrated in Fig. 7. The body is provided with a spindle 4 upon which the capstan is mounted.

It is desirable that the capstan may be suitably floated in the air while the rope is 100 being arranged for use and when in use, with the line of strain represented by the direction of the rope at 5 in a plane perpendicular to the spindles and that it may be maintained in this position with some rigidity 105 when the handle 3 is operated. For these purposes I project the point of support of the part 2 to a considerable distance

from the axis of the spindle 4, namely to some such point as 6, and inwardly substantially into line with the direction of the rope at 5, by means of a hook 7 and connection 8.

Whether the hook be directly or indirectly connected with the support by which the strain is to be received this gives me a long rigid connection from the point 6, 10 substantially tangent to the capstan surface at the point where the rope is received, *i. e.* the receiving portion of the surface, resisting end-for-end rocking of the capstan by reason of the operation of the handle. 15 As the coils of rope are wound upon the capstan they slide down its curved surface as at 9 and re-arrange themselves continuously and progressively, substantially as shown in Fig. 2. Substantially the same 20 portion of the length of the drum surface is constantly receiving the rope as the latter is drawn in and this portion of the surface is referred to by me as the receiving surface. The end 10 of the rope is held taut 25 to maintain the grip of the rope upon the capstan drum.

To assist in fixing the position of the rope as it is led into the capstan, I provide a guide comprising outwardly extending arms 30 11, 12, laterally turned in opposite directions at 13, 14 to provide a passage between which I prefer to extend in a lateral direction, transversely to the rope and parallel to the base of the capstan, sufficiently so 35 that the rope within may pass through in a direction tangent to the surface of the capstan in all of the intended directions of rope strain.

It will be seen that the guard or guide 40 provided permits insertion of the rope sideways by passing it to one side of the one pin and to the other side of the other pin.

Upon the end of the frame 2 farthest from the hook 7, I provide a becket 15 by which 45 my capstan block and hook as a unit may be united to a rope or form a combination with a sheave block, as in Figs. 4 and 5. I form openings 16 and 17 at any suitable point in the hook member to afford connection 50 with other parts similar to that, for example, seen in Fig. 6.

In Figs. 4 and 5 a pair of double sheave blocks and hooks are united to my capstan block in such a way as to make the capstan 55 act with one or more sheaves in a new combination to form a tandem capstan and sheave unit. The manner in which a tandem capstan and sheave may operate with a double sheave block in which the sheaves are preferably in tandem, is seen in Fig. 6.

In Figs. 4 and 5 the double sheave block 18 is connected with the becket by a hook 19 and the rope is passed about one sheave of the double sheave block 20 then about 60 one sheave of the block 18, then about the

second sheaves of blocks 20 and 18 in turn and secured to the becket 21. The hook 22 is adapted for engagement with the load.

Obviously, the operation of the floating capstan in tandem with pairs of sheave 70 blocks at 18 and 20 is similar to the operation of the capstan with a single block at each place.

In each case it is desirable to have the capstan and nearer sheave or sheaves of such 75 dimensions that the rope passing to the receiving surface of the capstan is clear of the rope passing about the sheaves and this can be accomplished by making the capstan at the point at which it is engaged 80 by the rope slightly larger than the pulley.

In the arrangement shown in Figs. 4 and 5 the greater strain will lie in the direction of the line joining the two pulley blocks and the composite line of strain will differ 85 but little from this. In order to balance the parts, I have preferred to place the becket 15 in such position that the line 23 indicating the axis of the rope under strain in Fig. 1 and the line 23' passing through 90 the center of the becket and transversely through the axis line of the capstan shall meet approximately at the point 6 where the hook is adapted to receive the strain.

In Fig. 6 I have shown the floating capstan member as comprising a frame 2' connected with a hook member 7' at one end and a becket member 15' at the other, carrying precisely the same capstan equipment as in Fig. 2 and a sheave 24 in tandem with 95 the capstan and smaller than it.

Describing the ratchet capstan now more particularly, the drum 1 is recessed at 25 to receive an annular row of ratchet teeth 26 mounted upon the frame. These teeth 105 are under-cut at 27 and are engaged by the top-raked nose 28 of a pawl 29 having a cylindrical body fitting within the cylindrical opening 30 and pressed longitudinally of it by spring 31.

The same cylindrical opening 30 extends clear through the capstan drum and contains a second pawl 32 also having a cylindrical body and having a nose 33 similarly top-raked to engage with the under cut 115 faces 34 of ratchet teeth 35, annularly arranged about the face of the handle 3 around a circle whose center is the pin 4.

I find that there is no necessity for keying these pawls to prevent rotation of the 120 pawls themselves as the coaction of the top rake of each of the pawls with the under-cut faces of the ratchet teeth and the coaction of the faces 36 of the pawls with the correspondingly sloped faces of the ratchet 125 teeth hold the pawls in position.

The same spring 31 presses both pawls 29 and 32 to their duty, the back of each pawl forming an abutment for exerting pressure against the other.

The sheave 24 is mounted upon a pin or spindle 37 secured at 37' and is guarded to prevent accidental displacement of the rope by a preferably arced rib 38. The sheave 5 is smaller than the receiving portion of the surface of the capstan drum so that the portions of the rope 5 and 40 may not engage.

The sheave wheel 24 is laterally movable, 10 longitudinally of the spindle 37 so as to be free from the guard 38, permitting placement or removal of the rope and is held against accidental lateral movement by a stop 41 which may be pivoted at any suitable point, as 42, and retained by a split 15 pin 43, passing through openings in it and also in the spindle or pin. Preferably the stop 41 is swung in this position a little beyond the center so that outward strain 20 upon it brought by lateral pressure from the sheave wheel shall tend to retain the locking means rather than to open it. A washer 44 is shown as receiving the wear from the pulley.

25 An additional means is provided for controlling the stop by which my sheave is retained in position. It is extended laterally in the form of an arm 45 which is formed into a hook 46 oppositely turned from the hook 47. The two hooks coöperate to form the becket 15'. The hook 47 is grooved at 48 in the form of an arc to receive the preferably lighter hook 46 so that no strain transversely to the spindle 37 will be 35 brought to bear upon the hook 46. The two hooks, however, together afford a separable closure for the becket which cannot be relieved except when the strain is removed and the attached rope has been 40 turned to a point upon the one hook where it will be free from the other, permitting movement of the arm 45. The closure of the becket in this manner also affords protection against accidental or careless release 45 of the sheave 24.

The body 48 (Figs. 6 and 8) forms a floating mount for two spindles 49 and 50 upon which two sheaves 51 and 52 are mounted and are laterally movable except 50 as they are held by stops. These sheaves are protected by preferably arced guards 53, 54 when in place, to prevent the rope from accidental disengagement; and the wheels are so proportioned that the rope 55 from the larger sheave runs outside of the rope for the smaller one, giving tandem arrangement of the sheaves without interference of the ropes.

I provide the body with a supporting hook 60 55 which is laterally displaced at 56 from the body to bring the line of support in line with the tandem wheels, and at the opposite end provide a becket which is similar to becket 15' and is similarly displaced at 57 to bring 65 it in line with the tandem wheels. It com-

prises a hook member 58 turned in one direction and recessed at 59 to receive laterally a hook member 60 turned in the opposite direction and carried by the end of locking arm 61. This arm is pivoted at 62 so as to engage 70 the washer 63 by its heel 64. It is retained in place by a split pin 65 and is also additionally held by the rope passing through the becket.

The washer 66 is held in place against the 75 sheave 51 by a locking arm 67, which is pivoted at 68 and engages the washer by means of its heel 69. This arm 67 is retained by the same split pin 65 as that which engages with washer 63 to retain sheave 52. 80

I contemplate applying my capstan sets to the handling of boats hung from ship davits among other uses and for this purpose I relieve the ropes of the strain under normal conditions by separate support of 85 the lower block from the upper block, as best shown in Fig. 6. This support is most conveniently obtained by means of a chain, as 70, removably secured at its ends to hooks 71, which hooks are riveted or otherwise fastened to the bodies of my blocks. In this manner the boats are held suspended without strain upon the rope until time for their use, when they may be handled readily and safely by one operator at each davit, lifting 95 the boats first sufficiently to release the chain.

It will be obvious that the strain may be maintained in line with the sheaves and with that portion of the length of the capstan drum upon which the rope is wound, 100 avoiding unbalancing strains.

It will be evident that the use of a continuous opening for my two pawls reduces the expense at the same time that it is more 105 convenient in operation and is more easily and effectively cleaned. The undercutting of the ratchet teeth and corresponding shape of the pawl tends to draw the pawl into the ratchet instead of tending to force it out of 110 the ratchet, thus avoiding one of the fruitful sources of slipping in ratchet work.

It will be further evident that the sheaves may be easily and quickly displaced laterally so that the rope may be fed about them 115 at any point in its length and that the rope may be connected directly from the capstan or over any desired arrangement of sheaves at any part of the haul to secure the speed required, pulling the load through its range 120 of greatest strain with one capstan and sheave combination and finishing the pull with another.

It will be further evident that the capstan and hook are independently self-aligning to 125 get the best results and may be used alone for a quick pull, even where a pulley is attached to the same block body, as in Figs. 6 and 7 and that tandem pulley combinations therewith can be easily and quickly 130

effected, whether single or multiple blocks be utilized and whether a multiple block used have the sheaves in tandem or in parallel arrangement.

5 Having thus described my invention, what I claim as new and desire to secure by Letters Patent is:—

1. In a device of the character stated, a body portion, a hook at one end thereof, a 10 capstan and a sheave upon the body portion in tandem relation, the capstan being larger than the sheave and nearer the hook than the sheave, a circumferential guard for the sheave adapted to protect a rope upon 15 the sheave from interference by a rope upon the capstan, and operating means for the capstan.

2. In a device of the character stated, a pulley block body, a sheave thereon, a capstan mounted on one side of the sheave with the rope-receiving portion of its body in tandem arrangement with the sheave, a circumferential guard for the sheave between the sheave and capstan extending to the sides 25 of the sheave and a hook in tandem arrangement with the capstan and sheave and upon the opposite side of said sheave from the capstan.

3. In a device of the character stated, a 20 body portion, an annularly arranged ratchet

on the side face thereof, a spindle mounted in the center of the annulus, a capstan drum upon the spindle and having a passage throughout its length substantially parallel to the spindle, a handle rotatable about the 35 axis of the spindle, an annularly arranged ratchet upon the handle, facing the drum, a pair of pawls resting in opposite ends of the passage through the drum, adapted to positively engage the ratchets, and a common 40 spring for the pawls located between them.

4. In a device of the character stated, a floating body portion having undercut ratchet face teeth annularly disposed about one side face thereof, a spindle mounted in 45 the center of the annulus, a capstan drum upon the spindle having a passage extending within the drum parallel to the spindle, means for turning the drum and a spring-pressed pawl movable longitudinally in the 50 passage, supported thereby against transverse strains, and having the end of its engaging face projected laterally at the front as compared with a perpendicular to the plane of the annulus to fit the undercut of 55 the ratchet teeth.

EDWARD E. CHERRY.
